METHOD AND APPARATUS FOR CONTROLLING FLOW OF FLUIDS

Nico Borresen, Buffalo, N. Y., assignor to Nicostat Products Co., Buffalo, N. Y.

Application April 9, 1938, Serial No. 201,118

15 Claims. (Cl. 137—139)

This invention relates to control of flow of fluids, and more particularly to a method and means for controlling flow of fluid fuels in connection with intermittently operating fuel burning apparatus.

One object of the invention is to provide an improved method of introducing a fluid fuel into the combustion chamber of a fuel burning apparatus in such manner as to eliminate the possibility of flare-backs and to provide for maximum 10 operating efficiency.

Another object of the invention is to provide an improved method and means for introducing a fluid fuel into the combustion chamber of a fuel burning apparatus at a varying rate and in accord with the fuel-consuming ability of the burning apparatus under different operating conditions.

Another object of the invention is to provide an improved method of introducing fluid fuel into the combustion chamber of an intermittently operated fuel burning apparatus including the provision of an initial fluid flow at a restricted rate during the early stages of each combustion operation and a full normal operating rate of flow 25 subsequent to a predetermined time lapse.

Another object of the invention is to provide an improved method and means for automatically varying the rate of fuel flow into the combustion chamber of a burning apparatus in such manner that during the initial stages of combustion operation the rate of fuel flow is restricted in a predetermined manner until such time as temperature and draft conditions in the burning apparatus assume substantially normal operating conditions, at which time a full flow 30 of fuel at the normal operating rate is permitted.

Another object of the invention is to provide an improved fluid control valve mechanism for the purpose described and in which resistance to fluid flow therethrough during normal full-flow operating conditions is at a minimum.

Another object of the invention is to provide an improved fluid control valve mechanism which is automatically operable in response to a control therefor to provide a slowly increasing rate of fluid flow therethrough for a predetermined time 45 during the valve opening process until full flow conditions are attained.

Another object of the invention is to provide an improved fluid control valve mechanism wherein the main valve element is adapted to be actuated toward open and closed positions by fluid pressure differential conditions operating upon the valve element, and in which movements 50

of the valve element in response to such fluid pressure differential forces thereof are automatically restricted in rate of motion in varying degrees.

5 Another object of the invention is to provide an improved valve motion restricting mechanism embodying a control member adapted to change in form in response to changes in the temperature thereof and a controlled electrically resistive conductor associated therewith for effecting changes in the temperature thereof, and means for effectively ventilating the elements of the mechanism so as to provide for quick response of the control element to temperature adjustments.

Other objects and advantages will appear in the claims and in the specification herein which is exemplary of the invention.

In the drawings:

Fig. 1 is a diagrammatic illustration of a fluid fuel burning apparatus employing a valve control mechanism of the invention;

Fig. 2 is a graphic illustration of movement of the main valve element of the fluid control mechanism during one complete hypothetical cycle of fuel burning operation;

Fig. 3 is a section through a valve mechanism embodying the principles of the invention;

Figs. 4 and 5, are views, on enlarged scales, of portions of the valve movement restricting mechanism of Fig. 3;

Fig. 6 is a view, similar to Fig. 5 of another form of construction of the valve movement restricting mechanism;

Fig. 7 is a transverse section on an enlarged scale through a portion of the mechanism of Fig. 3; and

Figs. 8 to 12 are diagrammatic views of portions of the fluid flow control mechanism of Fig. 3, showing the parts in different operative positions.

Referring to the drawings, the invention is shown as being supplied in connection with a fluid control valve structure that is particularly effective in connection with the control of fluids such as gaseous or liquid fuels in connection with fuel burning apparatus. Fig. 1 illustrates diagrammatically a furnace 10 arranged to be supplied with a gaseous or liquid fuel through means of a conduit 12, the flow of which is controlled by a valve mechanism 14 of my novel construction. The valve mechanism 14 is adapted to be controlled automatically by means of a thermostat device 16 which is connected in series with a source 18 of electric current and the valve actuating mechanism of the device.

The valve actuating mechanism of the device is adapted to provide for an initial opening of reduced size through the valve device in response to valve opening control movements of the thermostat 16, and a gradual increasing of the size of the opening through the valve device during an adjustable predetermined lapse of time prior to attainment by the valve of a completely opened position for full operating flow therethrough. Also, in response to valve closing movements of the thermostat device 16, the valve control mechanism is initially actuated to a reduced fluid flow position and then subsequently gradually actuated toward increasingly reduced flow positions until a completely closed valve position is attained. Hence, means are provided for introducing a reduced flow of fuel into the combustion chamber of a fuel burning apparatus during the early stages of combustion operation, and subsequently increasing the flow of fuel as temperature and draft conditions within the combustion chamber become such as to enable the device to accommodate increasingly greater rates of fuel flow, until full operating conditions are attained. Hence, the possibility of flare-backs due to overloading the combustion chamber prior to the attainment of normal operating conditions therein is avoided, along with the danger and noise that is otherwise attendant thereto. Also, in connection with the termination of the fuel burning process, the cessation of fuel flow is accomplished in a gradual manner, and hence the possibility of producing concussions in the fuel supply system is obviated, and the danger of accidentally extinguishing or disturbing the pilot light by such action is precluded. The fluid control features described generally hereinabove are adjustable for functioning in varying manners so that a wide range of variable performance characteristics may be obtained.

As illustrated more particularly in Fig. 3, the control valve mechanism herein includes a valve casing 30 provided with an inlet port 32, an outlet port 34, and an inner partition wall 36. An upper wall portion of the partition member is formed with a circular opening 38 into which is tightly fitted an upwardly extending cylindrical collar 40, the upper marginal edge portion of which is adapted to constitute an annular valve seat for the primary valve of the mechanism to be hereinafter described. Immediately adjacent and above the valve seat member 40 and in open communication with the inlet part 32 is provided a circular valve chamber 42 disposed in concentric relation with the valve seat member 40. The valve chamber 42 is of a diameter substantially greater than that of the annular valve seat member 40 and is adapted to freely accommodate therein a primary valve member 44 of disc form in such manner that the valve 44 is free to be moved vertically, as viewed in the figures, from a lowered valve seat contacting position to various raised positions to permit flow of fluid through the valve opening of the partition 36 of the device. The primary valve 44 is of a diameter slightly less than that of the valve chamber 42 so that a small annular-shaped gap 46 is provided between the marginal edge of the valve and the wall of the casing in the region of the chamber 42.

An auxiliary valve chamber 48 is provided in the upper interior portion of the casing 30 in open communication with the valve chamber 42 and is provided with an auxiliary outlet port 49 leading to the main outlet port 34 of the casing.

An auxiliary valve 50 for closing the auxiliary outlet port 49 is mounted in free-swivelling relation upon one end of a lever arm 52 by means of cooperation between a bifurcated finger piece 54 extending in spaced relation therefrom and an enlarged boss 56 formed integral with the auxiliary valve 50. The lever 52 is fulcrumed for pivotal action within the chamber 48 upon a downwardly extending portion of a bracket 58 which is rigidly mounted upon the casing structure. A coil spring 60 is arranged in such manner that one of its ends bears against the lever 52 at an end portion opposite to the auxiliary valve carrying end thereof and at a position spaced from the point of pivoting upon the bracket 58. The other end of the coil spring 60 bears against a shoulder piece 62 extending rigidly from a portion of the casing.

An electro-magnetic device comprising a coil 65, a core 66, and opposed pole pieces 67 and 68 is mounted upon the upper portion of the valve casing 30, with the ends of the poles 67 and 68 extending through suitable openings in the upper wall of the casing and their terminals disposed adjacent opposite ends of the lever 52. Suitable binding posts 70 are connected to opposite ends of the coil 65 for detachable connection thereto of conductors 72 arranged to provide a circuit in series with the source 18 of electric current and the control device 16. When the circuit is closed by operation of the device 16 the flow of current through the circuit energizes the coil 65 so that the lever is pivotally moved about the arm 58 in such manner that the auxiliary valve 50 is moved away from valve seat contacting position against the action of the spring 60. Whenever the electro-magnet actuating circuit is open, as by reverse operation of the device 16, the magnetic action of the poles 67 and 68 is terminated and the spring 60 causes the lever to return toward a position wherein the auxiliary valve 50 closes the auxiliary outlet port 49.

A valve movement restricting mechanism for the primary valve 44 is shown herein as comprising essentially a cantilever spring arm 80 formed of bi-metal in accord with conventional thermostatic practice so as to be adapted to bend in the presence of changing temperature conditions. The arm 80 is fixedly mounted at one of its ends to a stationary portion of the valve casing structure, as by means of a threaded pin and nut unit 82 (Fig. 4). The other end of the arm is connected to the main valve 44 through means of an intermediate adjustment leaf 84 and a swivel pin 86. The pin 86 is enlarged at its lower end and is provided intermediately thereof with a reduced section 88 (see Fig. 5) to provide for a swivel connection with opposed portions of a bifurcated clamp 90 which extends rigidly from the main valve. The upper terminal portion of the pin enlargement is formed to provide a rounded shoulder 92 for bearing against the under side of the leaf 84, and the upper reduced portion of the pin extends through a suitable opening in the leaf and is threaded to accommodate thereon a threaded nut 94 adapted to constitute a shoulder opposed to the shoulder 92 of the pin. A coil spring 96 is supported upon the reduced pin portion with its upper and lower ends bearing against the nut 94 and the leaf 84, respectively. The leaf 84 is preferably provided with a ferrule 98 disposed within the opening therethrough and having a beveled lower edge portion adapted to provide a swivelling fit be-

tween the leaf 84 and the rounded shoulder 92 of the pin.

An adjustment screw 100 is carried by the free end of the cantilever arm 80 in screwthreaded relation therewith (Fig. 7) and is arranged to have one end extending therefrom to bear against an intermediate portion of the leaf 84 to provide means for adjusting the attitude of the valve carrying end of the leaf 84 relative to the bi-metal arm 80.

An element for heating the bi-metal arm 80 is shown as comprising an electrically resistant conductor 105 in the form of a wire wound about the bowed or intermediate portion of the bi-metal arm 80 and having its opposite ends connected to binding posts 110 from which a pair of conductors 106 (Fig. 1) are arranged to lead to points of connection with the conductors 72 of the electro-magnetic control circuit. A switch 107 is preferably arranged in the line of one of the conductors 106 to provide for optional discontinuance of the operation of the heating element 105 independently of the control of the electro-magnetic operating circuit. The heating element 105 is electrically insulated in some suitable manner to prevent its being grounded upon the bi-metal arm 80, and such insulation is preferably provided of minimum thickness and heat insulating capacity so that the heat generated by transmission of electric current from the source 18 through the element 105 will be quickly and efficiently conveyed to the adjacent portion of the bi-metal arm 80.

When installed in the line of a fluid carrying conduit, as illustrated in Fig. 1, the valve device 35 is adapted to control the flow of fluid therethrough in a novel and advantageous manner in connection with a variety of applications. For example, application of the device to the control of fluid fuel flow into a heater apparatus, as shown in the drawings, will provide for improved combustion operation efficiency and will eliminate the possibility of certain undesirable occurrences and/or performance characteristics. In Figs. 3 and 8 the relative positions of the main and auxiliary valve members under normal valve closed conditions are shown as in the case when the control element 16 therefor is in inoperative condition and the electro-magnetic and heating element circuits are both open. There is thus illustrated the condition of the mechanism whenever it is inactive. Under such circumstances the electro-magnetic device of the mechanism is de-energized and the auxiliary valve 50 is seated in a closed position relative to the conduit 49, thus providing a built-up static fluid pressure within the valve chambers of the device above the main valve 44 by reason of which this valve is held firmly in a closed position against its valve seat 40, and flow of fluid through the conduit 12 is prevented. The operation of the static fluid pressure upon the upper surface of the valve 44 is produced by reason of the free passage of fluid from the inlet port side of the partition 36 through the gap 46 between the valve 44 and the adjacent wall portion of the valve chamber 42 and into the valve chambers above the main valve 44. Whenever the auxiliary valve 50 is closed the static fluid pressure of the line thus tends to maintain the main valve firmly seated in the closed position.

Whenever the control device 16 becomes adjusted to a circuit closing condition, as for example, in response to a reduction in the temperature of the atmosphere of the room adja-

cent thereto below a predetermined limit, or actuation of some time-controlled element, the electro-magnetic control circuit of the conductors 72 will be closed and the electro-magnetic device 5 of the mechanism will be caused to actuate the lever 52 as described hereinabove to raise the auxiliary valve 50 to an open position relative to the auxiliary conduit 49. When the auxiliary outlet port is thus opened the static fluid pressure 10 above the main valve 44 is relieved by escape of fluid from the valve chambers through the outlet ports of the mechanism, and the primary valve 44 becomes subjected to a differential of fluid pressure forces which is in favor of the forces tending to lift the valve away from its valve seat. The valve lifting forces referred to comprise dynamic fluid pressure forces due to flow of fluid from the inlet port and along side the marginal edges of the primary valve through 20 the gap 46 toward the outlet port and an unbalanced static fluid pressure force representing the difference between the static pressure of the line below the valve in the inlet end of the line and the static fluid pressure in the outlet end of the line. The composition of these valve lifting forces are more than sufficient to overcome the weight of the valve 44 and tend to lift it bodily within the valve chamber 42 away from the valve seat 40, and if left unrestrained would immediately move the valve 44 to its wide open position thus permitting a full normal operating flow of fluid through the mechanism immediately upon actuation of the control device 16 to operative position.

In the case of fluid fuel burning apparatus, such as industrial and domestic heating devices of the intermittently operating types, conditions within the combustion chamber of the heating apparatus in connection with a period of inaction are unsuited to full normal fuel burning operation because of insufficient draft and temperatures therein. If, under such conditions the firing operation is commenced by the immediate discharge of a full operating flow of fuel into the combustion chamber it is quite likely that concussions will take place within the combustion chamber during the initial stages of the starting up process, with the accompanying likelihood that the pilot light may be disturbed and that other dangerous and/or undesirable consequences may occur. Also, such operation involves waste of fuel, and hence a dangerous and uneconomical operation would result.

To correct the disadvantages of previous methods of fuel burning, applicant's mechanism 55 includes a valve movement restricting device, which, as shown herein, may be constructed as to comprise essentially the bi-metallic arm 80 and the heating element 105 therefor. The switch 107 is normally placed in a circuit-closed position, and consequently when the control device 16 is actuated to its circuit closing condition the heating element 105 is energized simultaneously with the energization of the electro-magnetic device. The bi-metallic arm 80 and its extension leaf 84 are so shaped and arranged as to normally provide, by means of the resiliency of the material from which they are formed, a cushioned resistance to upward movement of the valve 44, by 60 reason of the bearing of the leaf 84 against the shoulder 92 of the pin 86. The energization of the heating element 105, however, procures the generation of heat therein which gradually radiates therefrom and permeates the insulation thereof and reaches the adjacent portion of the

bi-metallic arm 80. As the generated heat permeates the bi-metallic arm 80 it causes the latter to change in shape in accordance with well known principles of the thermostatic art, and the parts are so arranged as to cause the arm 80 to tend to arch and to raise its outer free end upwardly, as viewed in the figures, under increasing temperature conditions. Thus, when the control device 16 is actuated to its circuit closing condition the auxiliary valve 50 is immediately opened and causes the creation of valve unseating fluid pressure forces tending to move the valve 44 toward its open position, but such motion is immediately resisted by the bi-metallic arm 80 which is in its normal or low arched condition. The arm 80, however, being in the form of a cantilever extension and being formed of metal, is somewhat resilient and functions in the manner of a spring, permitting the valve 44 to move a slight distance away from its seat 40 in response to the fluid pressure forces hereinabove described. Thus, an initial flow of fuel of reduced proportion is permitted into the combustion chamber of the device for ignition by means of a pilot flame or any other suitable form of igniter as may be desired. This initial combustion is amply accommodated by the reduced draft and temperature conditions in the combustion chamber at the moment, and provides for heating the combustion chamber and the establishment of a smooth flowing draft through the flue of the device. As the temperature within the combustion chamber rises, due to the initial combustion process, the fuel burning apparatus becomes progressively capable of accommodating increased flow of fuel, and the bi-metallic heating element of the device is so arranged as to provide for a gradual changing of the shape thereof over a predetermined lapse of time in such manner that the restraint of motion of the main valve 44 is gradually released as the generated heat permeates the bi-metallic element, to permit the valve 44 to be moved in response to fluid pressure forces thereon to increasingly higher positions and toward the full open position indicated in Fig. 9. Hence, means have been provided for restraining the movement of the valve element of the mechanism during the valve opening process in such manner as to permit a varying flow of fuel through the device in accord with the capacity of the fuel burning portion of the apparatus during the starting-up process. Obviously, the bi-metallic arm 80 may be formed in any desired manner to provide any desired heat responsive action characteristics. The extension piece 84 may similarly be so formed and arranged as to cooperate in the provision of different desired performance characteristics, and the adjustment screw 100 may be adjusted at will to vary the performance characteristics under any given circumstances to meet different operating conditions. For example, the adjustment screw 100 may be manipulated to correct the functioning of the device under different outside temperature conditions. For instance, it will be apparent that if the normal temperature of the atmosphere surrounding the valve device in connection with any given installation is higher than the normal temperature of the atmosphere surrounding the valve device in another given instance, it will be necessary to adjust the setting of the adjustment screw 100 accordingly, so that an initial restraining action against movement of the main valve 44 will exist immediately upon opening of the auxiliary valve 50 until after a predetermined time has elapsed.

Fig. 9 illustrates the position of the valve and valve movement restraining element whenever the full unrestrained effect of the valve lifting fluid pressure forces is exerted upon the valve by reason of the fact that the bi-metallic arm 80 has been changed in shape by the heat applied thereto to the point that the valve movement restraining elements have of their own accord moved to the position indicated by the position 5 of the fragmentary end portion of the leaf 84. Hence in this position, the bi-metallic arm, through the leaf 84, exerts no force upon the valve in either direction of its movement, and the main valve 44 is thus being supported in the 10 position shown by the fluid pressure forces exerted thereagainst which are caused by movement of fluid through the device. In many instances the movement of the valve 44 to the position shown in Fig. 9 will suffice to provide for sufficient flow of fluid through the mechanism in 15 view of the magnitude of the pressure existing in the line of the fluid source. In other cases, however, and whenever it is desirable to provide a valve device with a minimum pressure drop between the inlet and outlet ports thereof under full open conditions, the operation of the bi-metallic arm 80 may be availed of to relieve the fluid stream of the pressure-loss attendant to the 20 support of the valve member 44 in its full open position, as hereinabove described. In such case provision is made to enable the bi-metallic arm 80 to continue to rise upwardly at its outer or free end beyond the position indicated in Fig. 25 9 to the position indicated in Fig. 10 wherein the arm 80 and the leaf 84 have been moved to a super-elevated position and support the full weight of the valve 44, having raised the valve 44 upwardly and beyond its normal full open position of Fig. 9. Thus, the effective fluid carrying 30 capacity of the device has been increased. Hence, under this condition, no fluid pressure is required to support the valve and to maintain it in open position, and if the ports and chamber portions of the mechanism are provided of ample dimensions to suit any given condition of operation, the device will function with a minimum pressure loss between the inlet and outlet ports 35 thereof.

In connection with the valve closing operation 40 of the device, the main valve 44 is adapted to be actuated toward its valve seated position in response to actuation of the auxiliary valve 50, in a novel and advantageous manner. Closing of the auxiliary outlet port 49 by the auxiliary valve 50, as by pivotal action of the lever 52 in response to release thereof when the electro-magnetic device is de-energized upon actuation of the control device 16 to its inoperative position, terminates the previous flow of fluid from the 45 valve chamber 48 into the outlet port 34 and causes a sudden building up of static fluid pressure within the valve chamber and above the main valve 44 which tends to move the valve 44 downwardly toward its seated position. This 50 downwardly directed force upon the valve 44 is temporarily resisted, however, by the arm 80, but because of the resiliency of the spring 96 the valve 44 is motivated to some extent relative to the leaf 84, and a partial reduction of fluid flow 55 60 through the device takes place immediately and simultaneously with the closing of the auxiliary valve 50. However, the heating element 105 is also de-energized at the time of the de-energization of the electro-magnet and hence the bi-metallic arm begins to cool and tends to gradu- 65 70 75

ally assume its normal inoperative shape. As this cooling progresses the static fluid pressure above the valve 44 continues to urge the valve (Fig. 11) toward its seated position and in time this force is joined in its effect by a similarly directed force resulting from the creation of a suction adjacent the central lower surface of the valve 44 which is due to the creation of a vortex type of fluid flow through the opening of the partition 36 and toward the outlet port of the device. Also, as the valve 44 approaches its seated position and thus cuts off the volume of fluid flow through the device, the momentum of the fluid in the fuel discharge line provides an additional downwardly directed force upon the valve 44 in the form of an increased suction operating adjacent the underneath surface thereof.

Consequently, as the valve 44 approaches its seated position in response to relinquishment of upwardly directed supporting forces of the bimetallic arm 80, it comes successively into the range of additional and increasingly greater downwardly directed forces which increasingly overpower the resistance of the coil spring 96 and ultimately cause the valve 44 to be seated with a snap-like action (Fig. 12) despite the fact that the arm 80 has not yet assumed its normal inactive attitude. Hence, means have been provided for restraining the valve closing action of the device in such manner as to prevent the sudden cessation of fluid flow therethrough, such as would be undesirable in many types of application. For example, in connection with heating apparatus of the fluid fuel intermittently operating types, the sudden cutting off of the flow of fuel into the combustion chamber thereof will produce popping noises and concussions in the fuel line in accord with the principles of the well known hammer action of fluids under suppressed momentum conditions.

It will be apparent that the relation and interaction of the various valve opening and closing forces hereinabove described may be varied to suit different operating conditions and to give any performance characteristic that may be desired by varying the relative arrangements and proportioning of the actuating elements thereof, and by varying the relative adjustment of the elements of the device as provided for.

Fig. 6 illustrates another form of connection between the leaf 84 and the valve pin 86, wherein an adjustable abutting connection therebetween is provided. In this form of construction the pin 86 is threaded through a boss 83 carried by the leaf 84 for vertical adjustment relative to the leaf 84 by manual turning of the pin 86 as by means of a head 87 thereon and abuts, at its lower end the upper surface of the valve 44. Hence, no resiliency is provided in the connection between the leaf 84 and the pin 86, and during the valve closing movements of the mechanism the arm 80 has no restraining effect upon the valve 44, the valve 44 being free from the pin 86 for movement downwardly away therefrom. In some types of applications this form of construction will operate quite satisfactorily, and may even be preferred, according to the type of performance characteristics desired. The boss 83 is preferably provided during the course of its construction and after being threaded, with a slot 85 extending substantially therethrough. The boss is then upset, as by pressing upon its opposite ends. There is thus provided a self locking threaded connection between the

boss 83 and the threaded portion of the pins 86 when threaded therein which will resist accidental relative displacement of the parts.

When used in connection with room heating apparatus it may be desirable during mild weather conditions to arbitrarily limit the heating degree of the apparatus to the end that a more steady and low-flame operation may be obtained as distinguished from a more intermittent and high-flame operation. In such case the switch 107 of the heating element circuit may be left open, and the bi-metallic arm 80 will therefore constantly tend to maintain its normal inactive shape and will operate constantly to restrict movement of the valve 44 in response to fluid pressure forces directed thereagainst whenever the auxiliary valve is opened. Consequently, wherever the control device 16 operates to cause the auxiliary valve 50 to open, the main valve 44 will be opened to only some slight degree in response to fluid pressure forces thereagainst, and the bi-metallic arm 80 will continue throughout the burning operation to maintain the valve in its partially open condition. The adjustment screw 100 may be manipulated to give any desired performance characteristics under such operating conditions.

It will be apparent that by reason of my novel construction, during operating conditions a constant flow of fluid will pass through the valve chambers of the device about the valve movement restrictive elements thereof in such manner as to effectively ventilate the valve chambers and adjacent portions of the valve structure to the end that no substantial amount of heat is permitted to be stored up in the structural elements thereof, as might otherwise occur from transfer of the heat generated by the heating element 105 to adjacent portions of the valve structure. Hence, immediately upon disruption of the heating element circuit in response to valve closing adjustment of the control element 16, the bi-metallic arm 80 will commence to cool and the valve closing operation will therefore not be unduly delayed, as would otherwise occur if heat had been stored in the adjacent valve structure during the valve open cycle of the operation.

It will be apparent that application of the principles of the present invention are not to be limited to the use of a valve movement restraining element of the specific form illustrated and described hereinabove, and that any other suitable form of heat responsive unit may be employed in lieu of the bowed bi-metal arm 80. For example, a monometal heat responsive unit of the types employed in the thermostat art, or any other unit which will have a tendency to change in shape under changes in temperatures thereof may be adaptable for use in connection with the invention. Also, it will be understood that the valve movement restricting feature of the invention may be employed in connection with valve operating mechanisms differing from the construction shown and described hereinabove without departing from the spirit of the invention and the scope of the claims hereinafter.

Fig. 2 illustrates graphically movements of the main valve 44 relative to the valve seat member 40 and the resultant varying volume of fluid flow through the device during a complete hypothetical cycle of valve opening and closing operation. The solid line curve of Fig. 2 illustrates the valve movement and varying rate of fluid flow in the case of the form of valve construction illustrated in Figs. 3, 5, and 8 to 12 inclusive, wherein the

arm 80 is connected through means of the leaf 84 to the valve 44 in such manner as to restrain both the opening and closing movements of the valve 44. The broken line curve of Fig. 2 illustrates graphically the difference between the movements of the valve member 44 and the resultant rates of fluid flow when the valve is associated with the restraining element 80 in the manner illustrated in Fig. 6 and the results obtained by the form of construction shown in Figs. 3 and 5 which are illustrated by the solid line curve. The point 200 indicates the rate of fluid flow immediately attained upon actuation of the auxiliary valve 50 to its open position before the heat generated by the element 105 penetrates the arm 80. The set screw 100 may be adjusted, if desired, to provide an initial tension between the arm 80 and the valve 44 tending to urge the valve downwardly against its seat to such degree that the alteration of fluid pressure forces upon the valve 44 upon the opening of the auxiliary valve 50 fails to effect a change of fluid forces sufficient to overcome the resistance of the arm 80 to upward movement of the valve 44. In such case, the point 200 on the curve will indicate the rate of fluid flow through the auxiliary port 49 and the gap 46 around the main valve of the device. However, if the set screw 100 is adjusted to a position whereby there is a relatively reduced initial tension between the arm 80 and the valve 44 tending to resist upward movement of the valve, the point 200 on the curve will indicate an increased initial rate of fluid flow comprising a combination of the flow through the auxiliary port 49 and a restricted flow between the valve 44 and the valve seat element 40 which results from a slight upward movement of the valve 44 in response to the creation of a fluid pressure force differential tending to raise the valve 44 which overcomes the tension of the arm 80 immediately upon opening of the auxiliary valve 50.

The portion of the curve between points 200 and 202 indicates the time lapse between the initial opening of the auxiliary valve 50 and the beginning of the relinquishment of the valve restraining action of the arm 80 as a result of the penetration of heat thereto from the heating element 105. The portion of the curve between points 202 and 204 indicates the slow upward movement of the valve 44 and the increasing rate of fluid flow through the device as the bi-metallic arm 80 yields upwardly to the fluid pressure force differential hereinabove described, which tends to lift the valve 44 to the position shown in Fig. 9. The portion of the curve between points 204 to 206 indicates the further upward movement of the valve and the increased rate of fluid flow through the device in response to the positive lifting movement of the arm 80 which takes effect after the fluid pressure forces of the device have lifted the valve 44 to the utmost of their ability, and the portion of the curve between points 206 and 208 indicates the position of the valve 44 and the rate of fluid flow through the device when the valve is in the position shown in Fig. 10. The portion of the curve between points 208 and 210 indicates the movements of the valve 44 and the changing rate of fluid flow through the device subsequent to the closing of the auxiliary valve 50 in response to actuation of the control unit 16 toward the position indicated by Fig. 11; and, as explained hereinabove, during this portion of the cycle of operation the valve 44 comes progressively into the range of increasingly effective valve closing forces which ultimately overcome

the resistance of the coil spring 96 and cause the valve 44 to complete the terminal portion of its closing operation with a snap-like and positive seating movement (Fig. 12), as indicated by the curve below the point 210.

The broken line curve portions of Fig. 2 illustrate graphically the deviations of the movements of the valve 44 and of the resultant rates of fluid flow through the device from the performance of the valve as illustrated by the solid line curve that occur in connection with the use of the form of construction illustrated in Fig. 6. In this form of construction the valve restrictive element 80 is associated with the valve member 40 in abutting relation only, and therefore is only capable of restricting the opening movements of the valve 44. Consequently, as illustrated by the portion of the broken line curve between points 204 and 212, the valve 44 moves upwardly only as far as the open position indicated by the point 204, (Fig. 9), and is not carried further upwardly by any lifting action of the arm 80, as in the case of the first mentioned form of construction. Also, upon closing of the auxiliary valve 50, as at point 212 on the curve, the fluid pressure forces of the device act freely upon the valve 44 without restraint by the restrictive elements of the device and produce an immediately complete closing of the valve, thus cutting off all fluid flow therethrough. As explained hereinabove each of these forms of construction may have advantageous applications, depending upon the type of valve movement characteristics desired in any given instance.

Although only one form of the invention has been shown and described in detail, it will be apparent to those skilled in the art that the invention is not so limited but that various changes may be made therein without departing from the spirit of the invention or from the scope of the appended claims.

I claim:

1. A device for restraining movement of a valve relative to its seat, including a bi-metallic cantilever arm, a second arm mounted upon the free end of said bi-metallic arm and having a portion extending in spaced relation therefrom, means for adjusting the position of the extending end portion of said second arm relative to said bi-metallic arm, resilient means for connecting the outer extending portion of said second arm and said valve and controlled means for applying heat to said bi-metallic arm.

2. A device for restraining movement of a valve relative to its seat, including an element adapted to change in shape under changing temperature conditions, a second arm mounted upon the free end of said shape changing element and having a portion extending in spaced relation therefrom, means for adjusting the position of the extending end portion of said second arm relative to said shape changing element, resilient means for connecting the outer extending portion of said second arm and said valve and controlled means for applying heat to said shape changing element.

3. In a fluid control valve mechanism, inlet and outlet chambers adjacent one another and divided by a partition member defining a valve seat portion therebetween, a static fluid pressure chamber in open communication at one end with said inlet chamber and provided with an auxiliary conduit in open communication with said outlet chamber, a relatively light weight primary valve disposed in freely movable relation in said

pressure chamber, an auxiliary valve member adapted to close said auxiliary conduit between said pressure chamber and said outlet chamber, and means for moving said auxiliary valve to and from closed positions relative to said conduit to vary the static fluid pressure within said pressure chamber, whereby said primary valve is actuated by combined dynamic and static fluid pressure differentials upon opposite sides thereof relative said valve seat portion, and means resiliently resisting movement of said primary valve for delaying the operating movements thereof.

4. In a fluid control valve mechanism, inlet and outlet chambers adjacent one another and divided by a partition member defining a valve seat portion therebetween, a static fluid pressure chamber in open communication at one end with said inlet chamber and provided with an auxiliary conduit in open communication with said outlet chamber, a relatively light weight primary valve disposed in freely movable relation in said pressure chamber, an auxiliary valve member adapted to close said auxiliary conduit between said pressure chamber and said outlet chamber, and means for moving said auxiliary valve to and from closed positions relative to said conduit to vary the static fluid pressure within said pressure chamber, whereby said primary valve is actuated by combined dynamic and static fluid pressure differentials upon opposite sides thereof relative said valve seat portion, and means resiliently resisting movement of said primary valve away from said valve seat portion for delaying the valve opening operation thereof.

5. In a fluid control valve mechanism, inlet and outlet chambers adjacent one another and divided by a partition member defining a valve seat portion therebetween, a static fluid pressure chamber in open communication at one end with said inlet chamber and provided with an auxiliary conduit in open communication with said outlet chamber, a relatively light weight primary valve disposed in freely movable relation in said pressure chamber, an auxiliary valve member adapted to close said auxiliary conduit between said pressure chamber and said outlet chamber, and means for moving said auxiliary valve to and from closed positions relative to said conduit to vary the static fluid pressure within said pressure chamber, whereby said primary valve is actuated by combined dynamic and static fluid pressure differentials upon opposite sides thereof relative said valve seat portion, and means for temporarily restraining movements of said primary valve throughout a predetermined time period.

6. In a fluid control valve mechanism, inlet and outlet chambers adjacent one another and divided by a partition member defining a valve seat portion therebetween, a static fluid pressure chamber in open communication at one end with said inlet chamber and provided with an auxiliary conduit in open communication with said outlet chamber, a relatively light weight primary valve disposed in freely movable relation in said pressure chamber, an auxiliary valve member adapted to close said auxiliary conduit between said pressure chamber and said outlet chamber, and means for moving said auxiliary valve to and from closed positions relative to said conduit to vary the static fluid pressure within said pressure chamber, whereby said primary valve is actuated by combined dynamic and static fluid pressure differentials upon opposite sides

thereof relative said valve seat portion, and means for restraining movements of said primary valve including a bi-metallic element and a heat supply means associated therewith.

5 7. In a fluid control valve mechanism, inlet and outlet chambers adjacent one another and divided by a partition member defining a valve seat portion therebetween, a static fluid pressure chamber in open communication at one end with said inlet chamber and provided with an auxiliary conduit in open communication with said outlet chamber, a relatively light weight primary valve disposed in freely movable relation in said pressure chamber, an auxiliary valve member adapted to close said auxiliary conduit between said pressure chamber and said outlet chamber, and means for moving said auxiliary valve to and from closed positions relative to said conduit to vary the static fluid pressure within said pressure chamber, whereby said primary valve is actuated by combined dynamic and static fluid pressure differentials upon opposite sides thereof relative said valve seat portion, and means for restraining movements of said primary valve in varying degrees in accord with predetermined time lapses including a heat responsive element and a heat supply means associated therewith and means for controlling the supply of heat to said element in such manner as to vary the restraining effect of said element according to predetermined conditions.

8. In a fluid pressure control valve mechanism, inlet and outlet chambers separated by means defining a valve seat, a pressure chamber in open communication with said inlet chamber, a control element normally held in a closed position relative to said valve seat by the pressures existing in said pressure chamber and having intermediate and open positions, means operated in response to a change in a predetermined atmospheric condition for communicating said pressure chamber with said outlet chamber to thereby release the pressure on said control element to cause movement thereof to its intermediate position, whereby fluid pressure flows from said inlet chamber to said outlet chamber urging said control element toward its open position, and means controlled by said condition responsive means for subsequently permitting movement of said control element to said open position.

9. In a fluid pressure control valve mechanism, inlet and outlet chambers separated by means defining a valve seat, a pressure chamber in open communication with said inlet chamber, an auxiliary chamber joining said pressure chamber and said outlet chamber, an auxiliary valve closing said pressure chamber from said outlet chamber, a control element normally held in a closed position relative to said valve seat by the pressures existing in said pressure chamber and having intermediate and open positions, means operated in response to a predetermined atmospheric condition for actuating said auxiliary valve to thereby release the pressure on said control element to cause movement thereof to its intermediate position, whereby fluid pressure flows from said inlet chamber to said outlet chamber urging said control element to its open position, and means controlled by said condition responsive means for subsequently permitting movement of said control element to said open position.

10. In combination, a valve, means defining a pressure chamber adjacent said valve whereby said valve moves between first and second valve positions during pressure changes in said cham-

ber, and interrupting means including a bimetallic element operative to stop valve movement for a time period while said valve is moving from said first to said second position at a position intermediate said first and second positions, and means responsive to a predetermined atmospheric condition for increasing the pressures in said pressure chamber whereby said pressures act upon said valve against the action of said interrupting means when said valve is moving from said second to said first position in the course of its normal operation.

11. In combination, a valve comprising a floating disc adapted to be moved between first and second positions by the pressure of the fluid controlled by said valve, means for controlling said fluid pressure to actuate said disc, interrupting means comprising a bi-metal element providing a stop for said disc to stop movement thereof at a position intermediate said first and second positions for a predetermined time while moving from said first position to said second position, a heating element associated with said bi-metal element whereby the latter is caused to move away from said disc and permits movement thereof to said second position, said interrupting means being ineffective to stop movement of said disc when the latter is moving from said second position to said first position, and means responsive to a predetermined atmospheric condition for energizing said heating element.

12. In combination, a valve comprising a floating disc adapted to be moved between first and second positions by the pressure of the fluid controlled by said valve, means for controlling said fluid pressure to actuate said disc, and interrupting means including a timing device operative to stop movement of said disc at a position intermediate said first and second positions for a predetermined time while moving from said first to said second position, said interrupting means being ineffective to stop movement of said disc while the latter is moving from said second position to said first position in the course of its normal operation.

13. In combination, a valve comprising a float-

ing disc adapted to be moved between first and second positions by the pressure of the fluid controlled by said valve, means for controlling said fluid pressure to actuate said disc, interrupting means including a timing device operative to stop movement of said disc at a position intermediate said first and second positions for a predetermined time while moving from said first to said second position, said interrupting means being ineffective to stop movement of said disc while the latter is moving from said second position to said first position in the course of its normal operation, and means responsive to a predetermined conditioning for controlling said interrupting means.

14. In combination, a valve comprising a floating disc adapted to be moved between first and second positions by the pressure of the fluid controlled by said valve, means for controlling said fluid pressure to actuate said disc, means for actuating said controlling means, and interrupting means including a timing device operative to stop movement of said disc for a predetermined time at a position intermediate said first and second positions while said disc is moving from said first to said second position, said interrupting means being ineffective to stop movement of said disc when the latter is moving from said second position to said first position.

15. In combination, a valve comprising a floating disc adapted to be moved between first and second positions by the pressure of the fluid controlled by said valve, means for controlling said fluid pressure to actuate said disc, means for actuating said controlling means, and interrupting means including a timing device operative to stop movement of said disc for a predetermined time at a position intermediate said first and second positions while said disc is moving from said first to said second position, said interrupting means being ineffective to stop movement of said disc when the latter is moving from said second position to said first position.

16. In combination, a valve comprising a floating disc adapted to be moved between first and second positions by the pressure of the fluid controlled by said valve, means for controlling said fluid pressure to actuate said disc, means for actuating said controlling means, interrupting means including a timing device operative to stop movement of said disc for a predetermined time at a position intermediate said first and second positions while said disc is moving from said first to said second position, said interrupting means being ineffective to stop movement of said disc when the latter is moving from said second position to said first position, and means responsive to an atmospheric condition for controlling said interrupting means.

NICO BORRESEN.
